UNITED STATES PATENT OFFICE.

ARTHUR J. HALL, OF WILKINSBURG, PENNSYLVANIA, ASSIGNOR TO WESTINGHOUSE ELECTRIC AND MANUFACTURING COMPANY, A CORPORATION OF PENNSYLVANIA.

CONTROL APPARATUS.

1,249,746.

Specification of Letters Patent. Patented Dec. 11, 1917.

Application filed November 5, 1915. Serial No. 59,831.

To all whom it may concern:

Be it known that I, ARTHUR J. HALL, a subject of the King of England, and a resident of Wilkinsburg, in the county of Allegheny and State of Pennsylvania, have invented a new and useful Improvement in Control Apparatus, of which the following is a specification.

My invention relates to controllers for electric motors and particularly to apparatus of the master-controller type that is adapted for use in multiple-unit control systems of electric vehicles.

One object of my invention is to provide an auxiliary controller for a drum controller which shall be detachably mounted thereon and which shall govern the operation of the drum controller and control all circuits passing therethrough.

20 A further object of my invention is to provide an auxiliary controller of the above indicated character which shall automatically break all control circuits and effect automatic operation of the power-actuated brakes of the vehicle in case the operator of the controller becomes incapacitated through illness or sudden death.

Another object of my invention is to provide means for allowing the breaking of control circuits on both the main and the reversing drums, but preventing the automatic setting of the vehicle brakes when the main controller drum is normally returned to its off-position.

35 More specifically, my invention embodies an auxiliary controller which may be detachably mounted upon the usual drum controller and be provided with an auxiliary contact drum and an auxiliary shaft that 40 are joined to the shaft of the main controller drum, and an extension shaft joined to the shaft of the reversing drum. The auxiliary drum is initially joined to the auxiliary shaft by a spring under tension 45 but may be rigidly joined thereto by a spring-operated clutch in order that the auxiliary drum and the auxiliary shaft may be moved together when the clutch is operated by pressure applied to the controller 50 handle as the same is rotated, and in order that the auxiliary drum may be returned to an initial position separate from the auxiliary shaft in case the controller handle is released when in any operated position. A 55 fluid-pressure mechanism, which is con-

trolled by the auxiliary drum and the auxiliary shaft, is rotatably mounted upon the extension shaft of the reversing drum.

In the accompanying drawings illustrating my invention, Figure 1 is a diagrammatic sectional view of a drum controller provided with an auxiliary controller constructed in accordance with my invention; Fig. 2 is a sectional view taken along the line A—A of Fig. 1, and Fig. 3 is a detail view of the auxiliary contact drum shown in Fig. 1.

Referring to the drawing, a drum controller 1, embodying a main contact drum 2 and its shaft 3 and a reversing contact drum 4 and its shaft 5, is provided with an auxiliary controller 6.

The auxiliary controller 6 is provided with an auxiliary shaft 7 which is rigidly joined to the main shaft 3 and on which is rigidly mounted a support 8 for an auxiliary contact drum 9 and a base 10 for a controller handle 11. Furthermore, the auxiliary controller is provided with an extension shaft 12 which is rigidly joined to the reversing shaft 5 by a coupling 13, a fluid-controlling mechanism 14 which is rotatably supported upon a collar 15 of the shaft 12, a reversing handle 16 of the customary type which is detachably joined to the shaft 12, and a fluid valve 17.

The auxiliary drum 9 embodies a metal cylinder 18 which is mounted upon the support 8 and is held in position by collar 19 of the support 8, a collar 20 that is threaded to the cylinder 18, a cylinder 21 of insulating material which is supported between a rim 22 upon the cylinder 18 and the collar 20, and contact segments 23 which are mounted upon the cylinder 21 of insulating material. The contact segments 23 coöperate with a pair of contact fingers 24 which are carried by a suitable finger-base 24^a that is mounted upon the supporting frame 26. A concentric type coil spring 27, which is disposed between the support 8 and a collar 28, has its outer end joined to a lug 29 projecting down from the collar 20 and has its inner end joined to the collar 8.

A clutch 30, which rigidly joins the auxiliary drum 9 to the auxiliary shaft 7 when in operative position, comprises a plunger 31 movably mounted upon the shaft 7 but caused to rotate therewith by a key 50, a helical coil spring 32 surrounding the shaft 110

7 and mounted on the collar 19 which supports the plunger 31, and the cylinder 18. Projecting from the plunger 31 is a lug 33 which is adapted to fit within a pocket or slot 34 in the cylinder 18. A second projection 34^a on the plunger 31 is adapted to cooperate with a pin 35 for a purpose which will be explained later. Mounted upon the cylinder 18 is a lug 36 which engages an arm 37 of the fluid-controlling mechanism 14 when in the normal position and for a purpose which will be described later.

The fluid-controlling mechanism 14 embodies a body portion 38 which is rotatably mounted upon the collar 15 of the shaft 12, an arm 39 with lugs 40 and 41 which engage the pin 35 and a valve stem 42 of the valve 17, respectively, and the arm 37 which cooperates with the projection 36. The valve 17 embodies a body portion 43 which may be a portion of the supporting frame 26, a valve stem 42, a plug 44 mounted on said valve stem and a spring 45 which normally forces the plug 44 to its seat 44^a.

25 The rod 35 is mounted on lugs 25 and 46, and, by reason of pins 47 on the rod, it has a limited movement in a horizontal direction.

The controller handle 11 is pivoted on the base 10 at 48 and has a projection 49 that engages a key 50 which is mounted within a slot 51 of the auxiliary shaft 7. The movement of the controller handle in an upward direction is limited by a pin 52, which is mounted on the handle, and a latch 53 on the base 10. The key 50, which is operated by the controller handle 11, has a projection 54 which is disposed within a pocket 51^a of the plunger 31.

40 Assuming the controller parts to be in the position shown, the operation of the apparatus may be as follows: pressure is applied upon the handle 11 for causing the key 50 to force the plunger 31 down upon the cylinder 18, and then the controller handle is given a slight movement to the left which will allow the lug 33 of the plunger 31 to move into the pocket or slot 34 of the cylinder 18 to rigidly connect the auxiliary shaft 7 to the auxiliary drum 9, and which will cause the lug 34^a to move the pin 35 and arm 39 so that the spring 45 may close the valve 17. With the parts in this position, any movement of the controller handle will cause a like movement of the auxiliary drum 9 and the main drum 2.

However, should the controller handle be moved to any operative position, and the pressure thereon be removed, then the helical spring 32 acting on the plunger 31, will instantly raise the plunger 31, pin 50 and controller handle 11. The raising of the plunger 31 will disconnect the auxiliary drum 9 from the auxiliary shaft 7 because of removing the projection 33 from the slot

34, and, when this happens, the concentric spring 27, which, as before stated, is initially under tension and has one end rigidly connected to the shaft 7 and the other end rigidly connected to the drum 9, will instantly return the drum 9 to its initial position. As the drum 9 is returned to its initial position, the contact fingers 24 are disconnected from the contact segments 23 and thus break the power circuits, in accordance with a familiar practice, and the projection 36 upon the cylinder 18 comes into contact with the arm 37 of the fluid-controlling mechanism 14, which causes arm 39 and lug 41 to operate the valve stem 42 to open the valve 17 and thus operate the power-actuated brakes of the vehicle.

To again operate the controller, pressure must be applied to the controller handle after it has been returned to the illustrated off-position and a slight movement to the left given before any forward movement of the auxiliary drum 9, which controls the power circuits, is possible. However, when the auxiliary drum 9 is connected to the auxiliary shaft 7, the return of the controller handle to the off-position will break the power circuits by reason of the controller fingers 24 separating from the contact segments 23, but no operation of the valves 17 or setting of the power-actuated brakes is possible, as the lug 34^a on the plunger 31 engages the pin 35 which limits the movement of the controller handle before the lug 36 can engage the arm 37 to open the fluid valve 17.

Obviously, my invention is not restricted to the specific structural details and arrangement and location of parts herein set forth, as many modifications therein may be effected without departing from the spirit and scope of my invention, and such modifications are intended to be covered by the appended claims.

I claim as my invention:

1. In a removably mounted attachment for a controller, the combination of an auxiliary shaft, an auxiliary contact drum, a controller handle mounted on said auxiliary shaft, a clutch for joining said auxiliary shaft and said auxiliary drum, a spring for holding said clutch and said controller handle in a raised inoperative position, means for compressing said spring and for operating said clutch when pressure is applied to said controller handle, a second spring initially under tension, one end joined to said auxiliary shaft and the other end joined to said auxiliary drum, whereby should the controller handle be relieved of pressure thereon when in an operative position, the first-mentioned spring serves to raise said clutch to break the connection between said auxiliary shaft and said auxiliary drum and the second-men-

tioned spring serves to return said auxiliary drum to its initial position.

2. In a removably mounted attachment for a controller having a main contact drum and shaft and a reversing drum and shaft, the combination of an auxiliary shaft joined to the shaft of said main drum, an auxiliary contact drum and a controller handle mounted upon said auxiliary shaft, an extension shaft joined to the shaft of said reversing drum, a fluid valve, means mounted upon said extension shaft and controlled by said auxiliary drum and said auxiliary shaft for governing the operation of said fluid valve, a clutch for joining said auxiliary shaft and said auxiliary drum, a spring for holding said clutch and said controller handle in a raised inoperative position, means for compressing said spring and for operating said clutch when pressure is applied to said controller handle, a second spring initially under tension and having one end joined to said auxiliary shaft and the other end joined to said auxiliary drum, whereby the first-mentioned spring will raise said clutch to break the connection between said auxiliary shaft and said auxiliary drum and the second-mentioned spring will return said auxiliary drum to its initial position in case the controller handle is released when in an operative position.

3. In a master controller, the combination with a main contact drum, a shaft for said main contact drum, an auxiliary contact drum and a controller handle mounted on said main shaft, a reversing shaft, and a reversing contact drum and a fluid-control mechanism mounted on said reversing shaft, of a clutch for joining said auxiliary contact drum to said main shaft, a spring for holding said clutch and said controller handle in raised inoperative positions, means for compressing said spring and operating said clutch when pressure is applied to said controller handle, a second spring initially under tension and having one end joined to said main shaft and the other end joined to said auxiliary contact drum, whereby the first-mentioned spring will raise said clutch to break the connection between said main shaft and said auxiliary drum and the second-mentioned spring will return said auxiliary drum to its initial position and operate said fluid-control mechanism in case the

controller handle is released when in an operative position.

4. In control apparatus, the combination with a shaft and a handle secured thereto, of a clutch member loosely mounted on said shaft, a contact-carrying drum normally loosely inclosing said clutch member, means for biasing said clutch member and said handle to a raised inoperative position, means dependent upon the application of downward pressure to said handle for operatively mechanically connecting said shaft and said clutch member and effecting engagement of said member with said drum, and means acting between said shaft and said drum for returning the drum to its initial position after said biasing means has effected disengagement of said clutch member and said drum upon the release of said downward pressure.

5. In control apparatus, the combination with a shaft and a handle secured thereto, of an inverted cup-shaped clutch member loosely mounted on said shaft, a contact-carrying drum normally loosely inclosing said clutch member, a helical spring surrounding said shaft within said cup-shaped clutch member for biasing said member and said handle to a raised inoperative position, and a sliding key actuated by the application of downward pressure to said handle for operatively connecting said shaft and said clutch member and effecting engagement of said member with said drum.

6. In control apparatus, the combination with a shaft and a handle secured thereto, of an inverted cup-shaped clutch member loosely mounted on said shaft, a contact-carrying drum normally loosely inclosing said clutch member, a helical spring surrounding said shaft within said cup-shaped clutch member for biasing said member and said handle to a raised inoperative position, and a second spring having its respective ends joined to said shaft and said drum for returning the drum to its initial position after said biasing spring has effected disengagement of said clutch member and said drum upon the release of said downward pressure.

In testimony whereof, I have hereunto subscribed my name this 29th day of Oct., 1915.

ARTHUR J. HALL.
